DOUBLE DRESSER

Ernest Herrmann, Westport, Conn., assignor to Heywood-Wakefield Company, Gardner, Mass., a corporation of Massachusetts

Application August 8, 1958, Serial No. 52,138

Term of patent 7 years

(Cl. D33—6)

Fig. 1 is a front view of a double dresser showing my new design;

Fig. 2 is a fragmentary sectional view on the line 2—2 of Fig. 1 but on a scale somewhat enlarged with respect thereto; and

Fig. 3 is a sectional view on the line 3—3 of Fig. 1. The sides and back of the dresser are plain and conventionally shaped.

The dominant features of the design are the parts shown in full lines.

I claim:

The ornamental design for a double dresser, substantially as shown and described.
